UNITED STATES PATENT OFFICE.

ANSEL FREELAND, OF NEVADA, IOWA.

VENTILATED CONTAINER.

Application filed August 23, 1923. Serial No. 658,920.

To all whom it may concern:

Be it known that I, ANSEL FREELAND, a citizen of the United States, and a resident of Nevada, in the county of Story and State 5 of Iowa, have invented a certain new and useful Ventilated Container, of which the following is a specification.

The object of my invention is to provide a ventilated container of simple, durable and 10 comparatively inexpensive construction.

More particularly, my invention relates to a container for holding fruits and vegetables for display purposes in grocery stores and markets.

15 My present invention is designed to contain various fruits and vegetables for display purposes and can be used in connection with my co-pending application for patent on a display counter, Serial No. 635,646, filed April 30, 1923.

Still a further object is to provide a container structure wherein the side and end walls thereof are provided with a plurality of spaced ribs, which extend inwardly so as 20 to prevent any of the commodities within the container from resting flush against the walls thereof.

Still a further object is to provide a plurality of openings arranged in the side and 25 end walls of the container between the ribs formed therein, so that the commodities within the container may not rest flush against the openings and thereby prevent proper ventilation.

30 Still a further object is to provide the bottom of the container with a plurality of up-struck ribs, so that the commodities placed within the container may not rest flush against the bottom thereof, but will be spaced somewhat therefrom, so that the 35 spaces between the up-struck ribs will permit air to circulate therethrough and around the commodities.

With these and other objects in view, my 40 invention consists in the construction, arrangement and combination of the various parts of my device, whereby the objects contemplated are attained, as hereinafter more fully set forth, pointed out in my claims, and 45 illustrated in the accompanying drawings, in which:

Figure 1 is a top plan view of one of my 50 ventilated containers.

Figure 2 is a side elevation of the same, 55 showing the depressions in the side walls, which form the ribs on the interior thereof,

together with the openings for ventilation purposes.

Figure 3 is an end view of the container.

Figure 4 is an enlarged, detail, sectional 60 view taken on the line 4—4 of Figure 2; and

Figure 5 is a sectional view of a portion of the container showing some commodities therein for better illustrating the invention.

In the accompanying drawings, I have 65 used the reference character A to indicate generally a sheet metal container, which is formed with a bottom 10, and walls 11 and side walls 12.

The upper edge of the end and side walls 70 are rolled, as at 13, for receiving a reinforcing wire 14.

The end walls midway between their sides and substantially near their upper ends are provided with handles 15. The handles 75 15 are secured by rivets 16 extending through the handle and the end walls.

The parts just described are of the ordinary construction.

It may be mentioned that the side walls 80 of the container, as well as the end walls thereof, are inclined downwardly and inwardly, so that the bottom of the container is of less size than the upper open top thereof.

85 The side walls 12 are provided with a number of depressions 17, which cause to be formed ribs 18 projecting inwardly into the container proper.

The depressions 17 which form the ribs 90 18 are spaced from each other, so as to leave a portion 19 between the ribs 18.

The portions 19 between the ribs 18 are provided with a plurality of openings 20 for ventilation purposes.

95 The end walls 11 are also provided with a plurality of spaced depressions 21, which cause to be formed ribs 22 on the inner side of the container. The spaces 23 between the ribs 22 are provided with openings 24 for 100 ventilation purposes.

The bottom of the container is provided with a number of up-struck spaced ribs 25, so that when commodities are placed in the container, they will not rest flush against 105 the bottom thereof, but will be supported by the ribs 25 in such a manner that air will be able to circulate around the commodities, and between the ribs 25.

110 The ribs 18 and 22 are spaced relatively close together, so that when any fruit or vegetable is placed within the container, it

will not rest flush against the sides or ends of the container, but will be held in irregular position as shown in Figure 5 of the drawings.

5. The ribs will prevent the vegetables from resting against the portions 19, and thus seal the openings 20 arranged therein, or the openings 24 arranged in the end walls 11. The depth of the depressions which form

10 the ribs may be varied as desired.

The providing of the ribs 18 and 22 will permit air to circulate through the container to such an extent that fruits and vegetables displayed therein will not rot and decay for want of ventilation.

In this connection, it may be mentioned that when oranges or such other articles are placed in a container where there are no ribs and no openings, the oranges near the 20 bottom of the container will rot and decay.

With my improved container construction, the danger of this is eliminated.

The ventilating feature, together with the arrangement of the spaced ribs is important 25 and gives me a container construction which is efficient.

It may be mentioned that in a great many stores where fresh vegetables and fruits are sold, the fruits and vegetables are ordinarily placed in containers for better display purposes. With my container, the fruit and vegetables can be properly displayed without the danger of the bottom portion thereof rotting and decaying.

30 35 Some changes may be made in the construction and arrangement of the various parts of my ventilated container, without departing from the essential features and purposes of my invention, and it is my intention to cover by my claims, any modified forms of structure or use of mechanical equivalents, which may be reasonably included within their scope.

I claim as my invention:

40 45 1. In a sheet metal container, comprising a bottom, two end walls and two side walls,

the end walls and side walls being inclined inwardly from their upper edge so that the bottom is of less area than the upper open side of the container, a number of spaced 50 upstruck ribs formed in the bottom of the container so that the lower side thereof may rest flush against a support, the side walls and the end walls having their upper edge formed with a bead, a reinforcing wire in 55 said bead, said side and end walls having a plurality of spaced inwardly extending depressions for forming spaced vertical ribs, said ribs terminating short of the top and bottom edges of said walls, the portion of 60 the walls between said ribs being provided with a plurality of spaced aligned ventilating openings as and for the purposes stated.

2. A sheet metal container comprising a 65 bottom, two end walls and two side walls, the side walls having spaced depressions formed therein for forming spaced inwardly extending vertical ribs terminating short of the top and bottom edges of said walls, 70 the material between said ribs having openings therein as and for the purposes stated.

3. A sheet metal container comprising a bottom, two end walls and two side walls, the side walls and the end walls having 75 spaced depressions formed therein for forming spaced inwardly extending ribs terminating short of the top and bottom edges of said walls, the material between said ribs having openings therein as and for the purposes stated.

4. A sheet metal container comprising a bottom, two end walls and two side walls, the side walls and the end walls having 85 spaced depressions formed therein for forming spaced inwardly extending ribs terminating short of the top and bottom edges of said walls and arranged in a vertical plane, the material between said ribs having openings therein and said bottom having upstruck ribs therein.

ANSEL FREELAND.
